UNITED STATES PATENT OFFICE.

SAMUEL BYROM, OF PHILADELPHIA, PENNSYLVANIA.

DESIGN FOR SHAWL FABRIC.

Specification forming part of Design No. 5,367, dated November 21, 1871.

To all whom it may concern:

Be it known that I, SAMUEL BYROM, of the city and county of Philadelphia and State of Pennsylvania, have invented and produced a new and original Design for Fabric, of which the following is a specification:

The nature of my design is fully represented in the accompanying photographic illustration, to which reference is made; and may be said to consist of a broken twill, presenting a wave pat-

tern, which has the appearance of a series of chains, each composed of O-shaped links, lying parallel to each other and running diagonally across the fabric, each two chains *a* being separated by diagonal ribs *b*.

I claim as my invention—

The design for fabric, as shown.

Witnesses: SAMUEL BYROM.
